[57] CLAIM

The ornamental design for a fastening strip for glass panel, as shown and described.

DESCRIPTION

FIG. 1 is a perspective view of a fastening strip for glass panel in accordance with the design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is an alternative embodiment thereof.

The broken line showing of the environmental structure is for illustrative purposes only and forms no part of the claimed design.
